UNITED STATES PATENT OFFICE.

HEINRICH LOEWY, OF BERLIN, GERMANY.

HERNIA-TRUSS.

SPECIFICATION forming part of Letters Patent No. 732,361, dated June 30, 1903.

Application filed August 10, 1896. Serial No. 602,237. (No model.)

To all whom it may concern:

Be it known that I, HEINRICH LOEWY, a subject to the King of Prussia, Emperor of Germany, and a resident of Berlin, in the Kingdom of Prussia, German Empire, have invented certain new and useful Improvements in Hernia-Trusses, (for which I have obtained a patent in Germany, dated December 31, 1895, not numbered yet,) of which the following is a specification.

My invention relates to an improvement in hernia-trusses of that class in which the hollow rubber or elastic pad is filled with water or any other suitable fluid. Trusses of this kind are known to be more convenient to the wearer than those with a solid or bolstered pad, as the pressure of the water-filled pad is more soft and yielding; but in many cases, and particularly in severe cases of scrotal hernia, trusses of this kind will fail to retain the hernia, because soft and yielding pressure of the pad gives way. To prevent this, I apply to the water-filled pad or cushion of the truss a suitable mechanical means for acting against the said water-filled pad a sideward pressure, the result of which is to force the fluid contents of the cushion into a predetermined direction, and in consequence the tension of the pad is concentrated to a comparatively small space on its lower surface. The said sideward pressure acting against the water-filled cushion deforms the shape of said cushion in such a manner as to place that part of its surface where the tension is greatest opposite the hernia which tends to escape, the said tension of the pad being strong enough to retain the hernia, which encounters the pressure in direct opposition. The said pressure though being soft is not yielding on account of the tension obtained by the apparatus of my invention, and the pad as a whole is nevertheless sufficiently soft to prevent inconvenience, even if a very strong mainspring be employed to force the pad against the rupture.

In the accompanying drawings, Figure 1 illustrates the improved hernia-truss in perspective view, the pad being shown in its normal state and shape. Fig. 2 is a similar view with the water-filled pad compressed by a spring applied to its side.

A is the pad, of rubber or other elastic ma-

terial, filled with water, glycerin, or other suitable fluid, the said fluid being filled into the hollow pad through a short flexible pipe a, 55 which when sufficient tension of the pad has been obtained is bound up to prevent the escape of fluid.

The belt is indicated by H and supports the pad A, to one side of which, corresponding with one edge of the belt, a flat metal spring B or a blade, strip, or band of other suitable material is secured in a manner to be more or less tightly forced against the pad A. As a suitable means to cause the said blade B to operate a pressure against the pad A, I employ a strap or band b, secured to the spring or blade B and having buttonholes to be fastened to a button c, projecting from the frame of pad A. The said button c may be replaced by a buckle or hook or other means to adjust the strap b, so as to act the desired degree of pressure against the pad A. By this means the pressure may be varied as desired, and if in the course of time the water-filled pad 75 A will lose part of its tension and become slack the pressure device B will serve to restore the required degree of tension by being tightened up to the pad.

As illustrated in the drawings, the spring 80 B has a natural tendency to lift from the pad, and no pressure is being acted against the pad if the strap b is being unbuttoned, as shown in Fig. 1; but in some cases it may be found useful to arrange the spring B in a 85 manner to normally exert its resilient pressure against the pad A, and in such case the strap or band b to tighten the spring up to the pad might be even omitted.

The spring B or blade, strip, or band may 90 be suitably fastened with its base to the mainspring, and if a rigid piece B be applied instead of a spring it may be hinged to the base of the pad.

I wish it to be distinctly understood that 95 the spring B or other pressure device which serves, as described, to exert a pressure against the pad to force its fluid contents into a determined direction does not increase or add to the pressure of the mainspring, 100 which forces the pad against the body. Auxiliary springs serving to increase the pressure of the mainspring are known and have been applied to trusses before; but my invention

consists in applying to a fluid-filled truss-pad means which by their own resiliency or by a tightening device act to force the contents of the pad into a determined direction which is 5 in a plane transverse to the back and contact portion, and thereby increase the tension of the pad on a predetermined space of its useful contact-surface.

I claim as my invention—

- 10 1. In a hernia-truss, the combination, with a belt, of an inflatable pad attached thereto, and a pressure device arranged on that side of the pad corresponding with one edge of said belt, and means for forcing and holding 15 said pressure device down upon the pad, so that when said pad is inflated it is caused to bulge from its normal shape, substantially as set forth.
- 20 2. In a hernia-truss in combination, a belt, an inflatable pad attached thereto arranged so as to lie against the rupture when the truss is applied and means for then flattening the pad thereby increasing the pressure against the rupture.

3. In a hernia-truss in combination, a belt, 25 a spring thereon bent upward, a strap with holes therein in connection with the spring and an inflatable pad secured to the belt so arranged as to lie between the rupture and the spring when the truss is applied and a 30 button on the pad adapted to then engage the strap thereby flattening the pad and increasing the pressure against the rupture.

4. In a hernia-truss, the combination, with a belt, of an inflatable pad attached thereto, 35 and means, attached to said belt at one edge of the same, for contracting the corresponding side of the pad, substantially as set forth.

5. In a hernia-truss, the combination, with a belt, of an inflatable pad attached thereto, 40 a spring secured to said belt and extending over said pad, a strap attached to said spring, and a button on said pad adapted to engage said strap, substantially as set forth.

HEINRICH LOEWY.
